UNITED STATES PATENT OFFICE.

GEORGE SCHNEIDER, OF BALTIMORE, MARYLAND, ASSIGNOR TO HERBERT R. OLIVER AND CLIFTON E. KREBS, OF SAME PLACE.

BIT-HOLDER FOR BRIDLES.

SPECIFICATION forming part of Letters Patent No. 617,300, dated January 3, 1899.

Application filed January 18, 1898. Serial No. 667,035. (No model.)

To all whom it may concern:

Be it known that I, GEORGE SCHNEIDER, a citizen of the United States, residing at Baltimore, in the State of Maryland, have invented certain new and useful Improvements in Bit-Holders for Horses' Bridles, of which the following is a specification.

This invention relates to a bit-holder for horses' bridles or halters; and the object of 10 the invention is to provide an improved construction of such devices suitable for use on horses in fire-engine houses, salvage-corps, and the like.

The invention is illustrated in the accompanying drawings, in which—

Figure 1 is a side view of the bit-holder. Fig. 2 is a vertical section of same. Fig. 3 is a side view of inner tube. Fig. 4 is a perspective view of the pivoted clip. Fig. 5 is a 20 perspective view of the screw-cap with hook. Fig. 6 is a view of part of a cheek-strap of a bridle and the clip pivoted thereto. Fig. 7 is a view of a bridle with a bit-holder attached and the outline of a horse's head shown in 25 broken lines.

The bit-holder is to be used on what may be termed either a "halter" or a "bridle" or a combination of both.

The letter A designates the headstall, b 30 the cheek-strap, c the nose-band, and d the throat-latch, all of which are ordinary parts of a halter or bridle.

When a horse is standing in a stable or is feeding—wherever he may be—the bit will be 35 removed from his mouth, and by reason of the action of the pivoted clip the bit will take position close below the animal's lower jaw. When it is desired to place the bit in the animal's mouth, it may be quickly done without 40 any adjustment of the halter or bridle parts already mentioned by merely drawing the bit downward, swinging the tube and clip on the pivot to place the bit in position to enter the mouth, and then releasing the bit.

45 The bit e has at each end the usual ring f, and its positions when in the animal's mouth and when out of it are shown in Fig. 7.

Two tubes g h are employed telescopically. The outer larger tube g has at its lower end a 50 screw ring or ferrule i with an inward flange i', which serves to stop the inner smaller tube

h from drawing entirely out by the outside flange j on its upper end contacting with said inward flange i'. A screw-cap k takes over and around the outer side of the upper end 55 of the large tube g. This cap has on its inside a suitable loop or hook k', to which one end of an extension spiral spring l is attached. This spring extends down through the inner small tube h, and its lower end is attached to 60 an eye m on the upper end of the snap-hook n, which screws through a cap o on the lower end of the small tube h. It will be seen that the spring l, attached at the upper end of the large tube and at the lower end of the small 65 tube, will normally keep the two tubes drawn together, as shown; but by drawing the snap-hook downward the spring will elongate and allow the tubes to be extended. Thus the tendency of the spring is to keep the top cap 70 k and the bottom cap o in their respective positions and prevent them from coming off.

I have provided a circular collar-clip p or split ring with two tightening-jaws p' and a set-screw q to bind them. An arm r projects 75 upward from the clip, and at its upper end has a pivot-hole r'. This device constitutes a pivoted clip or swinging clip for connecting the telescopic bit-holder with the cheek-strap b. It is loosely attached to the cheek-strap by a pivot-pin or rivet s, passed through the hole r' in such manner as to allow the clip-ring p to swing, as indicated in Figs. 6 80 and 7, and thereby take either of two positions. The clip-ring p takes around the larger 85 tube g, and the latter may be slipped upward or downward through the expanded clip-ring, as desired, to place the bit e normally at the required height to fit in the animal's mouth. When the bit has been properly adjusted, the 90 set-screw q on the clip may be tightened to bind the clip closely around the tube and hold it firmly. Thus after the pivot-pin or rivet s has permanently fixed the arm r to the strap b the construction of the split collar or clip-ring p will allow the telescopic bit-holder to 95 be vertically adjusted to suit the mouth of the animal on which the bridle may be used.

Having thus described my invention, what I claim is—

1. The herein-described telescopic bit-holder for bridles consisting of the outer tube,

g, having at its upper end a cap provided with an inside loop or hook, h'; an inner tube, h, having at its lower end a screw-cap, o; a snap-hook whose shank screws through the said screw-cap and has interiorly an eye, m; and an extension spiral spring passing through the said inner tube and having one end attached to said loop or hook on the upper cap, and the other end attached to said

10 eye on the shank of snap-hook.

2. The combination of the cheek-strap of a bridle or halter; a clip-ring having an upward-projecting arm whose upper end is pivoted to the said cheek-strap so as to allow a

pivoting movement; and a bit-holder firmly 15 held by said clip-ring.

3. The combination of the cheek-strap of a bridle or halter; a clip-ring pivoted to said cheek-strap; a tubular holder vertically adjustable through the said clip-ring; and a bit 20 attached to the holder.

In testimony whereof I affix my signature in the presence of two witnesses.

GEORGE SCHNEIDER.
